CLAIM

The ornamental design for a chamber as shown and described.

DESCRIPTION

FIG. 1 is a top right isometric view of a chamber showing our new design;

FIG. 2 is a bottom left isometric view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines throughout the drawing figures depict environmental holes that form no part of the claimed design.

1 Claim, 8 Drawing Sheets
